UNITED STATES PATENT OFFICE.

CHARLES J. ERICKSON, OF CHICAGO, ILLINOIS, ASSIGNOR, BY MESNE ASSIGNMENTS,
TO FIRST TRUST AND SAVINGS BANK, TRUSTEE, OF CHICAGO, ILLINOIS.

HARMONIC PARTY-LINE TELEPHONE-RINGER.

1,051,989.

Specification of Letters Patent. Patented Feb. 4, 1913.

Application filed August 11, 1906. Serial No. 330,191.

To all whom it may concern:

Be it known that I, CHARLES J. ERICKSON, a citizen of the United States of America, and resident of Chicago, Cook county, Illinois, have invented a certain new and useful Improvement in Harmonic Party-Line Telephone-Ringers, of which the following is a specification.

My invention relates to harmonic ringers for use in party line selective signaling systems.

The object of my invention is to provide improved means for supporting the striker or bell-clapper of a harmonic ringer, and to provide certain details and features of improvement and combinations tending to increase the general efficiency and serviceability of a harmonic ringer of this particular character, as will hereinafter more fully appear.

To the foregoing and other useful ends, my invention consists in matters hereinafter set forth and claimed.

In the accompanying drawings, Figure 1 is a front elevation of a harmonic bell or ringer embodying the principles of my invention. Fig. 2 is a detail front elevation of the striker and armature, together with mounting for the same, the striker-arm being broken away for convenience of illustration. Fig. 3 is a section on line 3—3 in Fig. 1. Fig. 4 is a section on line 4—4 in Fig. 2.

As thus illustrated, my improved ringer comprises a bracket-plate A upon which are mounted the usual gongs B, B. The permanent magnet C has its upper end suitably secured to a plate D, which latter is supported from the bottom of the plate A. The electro-magnets E have their upper ends secured to the plate D, and are arranged one at either side of the permanent magnet. The lower end of the said permanent magnet is provided with an opening c, as shown more clearly in Fig. 4. The striker F is supported on the usual striker-arm G, which latter has a springy or resilient portion g and a lower and enlarged threaded portion g¹. The armature H is secured to the said striker at a point just above the said springy or resilient portion g preferably by a screw h, whereby the arma-

ture can be moved up and down on the said striker-arm. The threaded portion g¹ of the said striker-arm extends downwardly through the opening c and is clamped in place by threaded clamping nuts g², said nuts arranged above and below the said lower portion or pole-piece of the said permanent magnet. With this arrangement the striker is flexibly mounted upon the permanent magnet, the striker-arm being all in one piece, the portion g insuring the requisite degree of flexibility. This portion g can, of course, be of any suitable degree of thickness or strength, whereby the different ringers on a party line can all be adapted to respond to ringing currents of different frequencies, each ringer being tuned, so to speak, to respond to some particular frequency.

It will be understood that the permanent magnet C has its upper end or pole-piece magnetically connected with the cores or pole-pieces of the electro-magnets.

What I claim as my invention is:—

1. In a bell or ringer, a permanent magnet, a spring extending from the said permanent magnet having a portion secured thereto, an armature supported by and mounted at right-angles to the end of said spring, a striker, a rod extending crosswise of the armature to connect the striker with the spring, electromagnetic means for operating said armature, and sound-producing means to be engaged by said striker, said armature adjustable relatively to the electromagnetic means and spring.

2. The combination of a permanent magnet, an electromagnet, a spring having one end thereof mounted on the permanent magnet, an armature having its middle portion secured at right angles to the spring, adapted to be adjusted lengthwise of said spring, and suitable means operated by said armature when the latter is vibrated by the electromagnet.

3. The combination of a permanent magnet, a two-core electromagnet, an armature having its end portions disposed opposite the two cores of the electromagnet, a spring mounted on the permanent magnet, said armature mounted upon and flexibly supported by said spring and adapted to be adjust-

ed lengthwise of said spring, and suitable means operated by the armature when the latter is operated by the electromagnet.

4. In a bell or ringer, the combination of 5 a permanent magnet, a striker provided with a spring having one end thereof secured to said permanent magnet, an armature supported by the other end of said spring, adapted to be adjusted lengthwise 10 of said spring, electromagnet cores having their ends disposed opposite the ends of said armature, and sound-producing means to be engaged by said striker when the armature flexibly supported by said spring is vibrated 15 by the said electromagnet cores.

5. In a bell or ringer, a permanent magnet, a striker-arm made in one piece and provided with a flexible portion and a screw-threaded portion, means for securing 20 the screw-threaded portion in an integral portion of the said permanent magnet, an armature and a striker mounted on the striker-arm above the flexible portion there-

of, electromagnets for operating said armature, and gongs to be engaged by said 25 striker.

6. The combination of a permanent magnet, a screw-threaded portion, means engaging said screw-threaded portion to adjustably hold the same in the end of said permanent magnet, a striker-rod provided with a striker, a spring integrally and flexibly connecting the said screw-threaded portion with the said striker-rod, an armature mounted crosswise of the striker-rod, electromagnet cores adapted to act on the opposite ends of said armature, and sound-producing means to be engaged by said 30 35 striker.

Signed by me at Chicago, Cook county, 40 Illinois, this 9th day of August, 1906.

CHARLES J. ERICKSON.
